CLAIM

The ornamental design for a control assembly for a materials handling vehicle as shown and described.

DESCRIPTION

FIG. 1 is a top, front, right side perspective view showing a control assembly of a materials handling vehicle;

FIG. 2 is a bottom, back, left side perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines illustrate portions of the control assembly for a materials handling vehicle which form no part of the claimed design.
